[57] CLAIM

The ornamental design for a video tape recorder, as shown and described.

DESCRIPTION

FIG. 1 is a top, front and right side perspective view of a video tape recorder showing our new design, during a turn-ON time;

FIG. 2 is a front elevational view thereof;

FIG. 3 is a top plan view thereof;

FIG. 4 is a right side elevational view thereof, a left side elevational view being a mirror image of the right;

FIG. 5 is a rear elevational view thereof;

FIG. 6 is a bottom plan view thereof;

FIG. 7 is a front elevational view thereof, with an operation section shown open;

FIG. 8 is a right side elevational view thereof, with an operation section shown open; and,

FIG. 9 is a top plan view thereof, with an operation section shown open.

FIG. 1

FIG. 2

FIG. 3

FIG. 4
